UNITED STATES PATENT OFFICE.

CHESTERFIELD F. COLE, OF LANSING, MICHIGAN, ASSIGNOR TO THE QUINCY KNITTING COMPANY, OF THREE RIVERS, MICHIGAN, A CORPORATION OF MICHIGAN.

KNITTING-MACHINE.

SPECIFICATION forming part of Letters Patent No. 773,477, dated October 25, 1904.

Application filed November 23, 1903. Serial No. 182,312. (No model.)

To all whom it may concern:

Be it known that I, CHESTERFIELD F. COLE, a citizen of the United States, residing at Lansing, in the county of Ingham and State 5 of Michigan, have invented certain new and useful Improvements in Knitting-Machines, of which the following is a specification, reference being had therein to the accompanying drawings.

10 The invention relates to knitting-machines of the type generally known in the art as "straight-knitting" machines; and it consists, primarily, in a novel construction of needle-bed therefor adapted to receive the needles 15 and to permit of angular adjustment of the same, whereby they may be withdrawn from or thrown into operative relation with the needle-operating cams.

The invention further consists in a new and 20 simple construction of needle-holder, in the formation of the adjusting and locking mechanism for the holder to retain the needles in different positions of adjustment, and, still further, in the peculiar arrangement and combination of other parts of the machine, as will 25 be more fully hereinafter set forth.

In the drawings illustrating my invention, Figure 1 is a vertical transverse section through a part of a straight-knitting machine, 30 showing the bed in section and the needle-holder and needle in elevation. Fig. 2 is an enlarged sectional perspective view of the needle-bed. Fig. 3 is a detached perspective view of one of the needle-holders, and Fig. 4 is a plan view of the needle-operating cams and bed.

In the drawings thus briefly described reference - letter A designates the needle-bed frame of the construction usual in straight-knitting machines.

B represents one of the needle-beds thereon, the complementary bed being omitted, as it is of similar construction, and the relative arrangement of the beds and the two series

of needles form no part of the present invention. 45

As shown in Fig. 2, the bed is interposed between two blocks C and D, bolted to the needle-bed frame, and is adjustably secured to these blocks in the usual manner by 50 laterally-extending screws or threaded bolts E.

To adapt the bed to receive the needle-holders and needles, a series of transverse slots, such as F, are formed therein, extending entirely across the bed, but only partly therethrough. Each slot, as shown, tapers vertically, increasing in depth from the front edge G of the bed to the rear edge H, as plainly indicated in Fig. 2. As thus constructed the bed has an underlying base-section I, which extends uninterruptedly its entire length, thereby forming a rigid and durable structure capable of withstanding the strain to which it is necessarily subjected. 65

Within the slots described are the needle-holders J, upon which are mounted the needles K, and K' represents the usual needle-retaining gib engaging a substantially bevelled grooved K² in the bed. 70

Each needle-holder is preferably formed of a single piece or strip of spring material, preferably wire, folded upon itself in the manner indicated in Fig. 3 to form a straight needle-supporting section a and bent to form 75 a spring locking-section b. The locking-section comprises a downwardly-extending loop c, the lower portion of which is bent forwardly to form a stop d, and a rearwardly-extending loop e, which forms a handle or finger-hold 80 by means of which the needle-holder is operated. At a slight distance beneath the loop e is a detent f, formed in the section c, adapted to engage a locking-bar hereinafter described to lock the needle-holder in its different positions of adjustment. The wire forming the loop e described extends forwardly in the direction of and partly over the needle-

retaining section and serves to grip and hold the needle, so that it may be shifted with the holder.

K^3 represents the universal locking-bar for 5 the series of needle-holders, spaced from the rear edge of the bed, as indicated, and having detachable connections therewith. More particularly the bar is separated from the bed by spacing-blocks L , which are bolted to the edge 10 of the bed, and is connected to these blocks by the screws M . Upon the inner face of the locking-bar is a rib O , and between this rib and the rear edge of the bed project the downwardly-extending portions c of the locking- 15 sections previously described, the detent f engaging upon the upper and lower edges of the rib.

P and Q are the usual wing cams, and R a V -cam, arranged above the bed in the usual 20 manner and adapted to be operated by a suitable mechanism. (Not herein shown.) As the means for operating the needles is of old and well-known construction and forms no part of the present invention, a further description of the same will not be necessary. 25

When it is desired to throw one or more needles into operative relation with the cams, the operator by grasping the handle portions of the needle-holders raises the same until further 30 upward movement is prevented by the stop d . At this moment the detent engages the upper face of the locking-bar K^3 and the needle is retained in a position with its heel a' extending above the surface of the bed in operative 35 relation to the cams, as plainly illustrated in Fig. 1.

To withdraw the needle, the holder is forced downwardly until the finger-section or handle strikes the locking-bar, and it is retained in 40 this position with the heel of the needle below the surface of the bed by the detent.

From the description of the mechanism as set forth it will be evident that by slotting the bed in such manner as to leave a solid unbroken 45 section underlying the slots a very durable construction is produced. Furthermore, the bed being in one piece there are no parts to become loose and thrown out of alinement. Thus the needles after the bed has once been 50 adjusted are always in operative relation to the corresponding series of needles.

The holders for the needles, as will be obvious, are of very simple construction, and while being capable of effectively performing the 55 function for which they are designed can be produced at very small cost.

What I claim as my invention is—

1. In a knitting-machine, the combination with a solid needle-bed having a series of trans- 60 verse slots formed therein and extending only partly therethrough, of a universal locking-bar separated from and having detachable connections with the bed, a plurality of needle-

holders arranged within the bed-slots for angular adjustment and carrying spring locking- 65 sections projecting between the bed and locking-bar and adapted to engage independently with the latter to maintain the holders in their different positions of adjustment, and the needles supported upon the holders. 70

2. In a knitting-machine, the combination with a needle-bed having a series of transverse slots formed therein, of a plurality of needle-holders within the slots, each of said needle-holders having a needle-supporting section 75 and a spring locking-section arranged to bear upon the needles and hold the same firmly to the needle-supporting sections, and needles supported upon the holders.

3. In a knitting-machine, the combination 80 with a needle-bed having a series of transverse slots formed therein, of a plurality of needle-holders within the slots, each formed of a single piece of spring material folded and bent to form respectively a needle-supporting section and a spring locking-section arranged to 85 bear upon and hold the needles firmly to the needle-supporting sections, and the needles supported upon the holders.

4. In a knitting-machine, the combination 90 with a needle-bed having a series of transverse slots formed therein, of a bar secured to said needle-bed in rear of said slots, a plurality of needle-holders arranged within the slots for angular adjustment, each formed of a single 95 piece of spring material having a substantially flat needle-supporting section and a downwardly-extending looped portion, one side of said looped portion being arranged to frictionally engage the forward edge of the 100 bar secured to the needle-bed to lock the needle-holders in various positions of adjustment.

5. In a knitting-machine, the combination with a needle-bed having a plurality of trans- 105 verse slots formed therein, of a bar secured to said bed in rear of said slots, a plurality of needle-holders arranged within said slots for angular adjustment, each formed of a single piece of spring material and having a substantially flat needle-supporting section, the rear 110 end of which is bent to form a looped portion, the free end of which is arranged to overlie the flat needle-supporting section and hold the needle firmly thereon and one side of which is arranged to frictionally engage the 115 side of the bar secured to the needle-frame and hold the needle-holders in various positions of adjustment, and the needles supported upon the holders.

6. In a knitting-machine, the combination 120 with a needle-bed having a plurality of transverse slots formed therein, of a bar secured to said bed in rear of said slots, a plurality of needle-holders arranged within said slots for angular adjustment, each formed of a single 125 piece of spring material and having a substan-

tially flat needle-supporting section, the rear end of which is bent to form a looped portion, the free end of which is arranged to overlie the flat needle-supporting section and hold 5 the needle firmly thereon and one side of which is provided with an outwardly-bent detent arranged to coöperate with the forward edge of the bar secured to the needle-bed to

lock the needle-holders in various positions of adjustment.

In testimony whereof I affix my signature in presence of two witnesses.
